SPRING SEAT CONSTRUCTION

Charles S. Viall, Sr., Los Angeles, and Stanley Overby, Inglewood, Calif.; said Viall assignor to said Overby

Application June 26, 1940, Serial No. 342,471

8 Claims. (Cl. 155—53)

Our invention relates to spring seat construction and more particularly to successive spring means that are arranged to successively come into play as increased pressure is applied to the seat.

It is also an object of our invention to provide means for varying this spring tension. Other objects are to provide increased comfort and resilience irrespective of the weight of the person sitting on the seat, economy in manufacture, general superiority and serviceability, relative simplicity, inexpensiveness in construction, and general efficiency.

The invention also comprises novel details of construction and novel combinations and arrangements of parts, which will more fully appear in the course of the following description. However, the drawing merely shows and the following description merely describes one embodiment of the present invention, which is given by way of illustration or example only.

In the drawing, like reference characters designate similar parts in the several views.

Figure 1 is a front elevation of an embodiment of our invention.

Figure 2 is a transverse section on the line 2—2 of Figure 1.

Figure 3 is a section taken on the line 3—3 of Figure 2.

Figure 4 is an enlarged, transverse section through spring means comprised in the embodiment.

Figure 5 is a section taken on the line 5—5 of Figure 4.

Figure 6 is a broken elevation, looking in the direction of the arrow A of Figure 4.

Figure 7 is a top view of a bracket comprised in said embodiment.

Figure 8 is a side elevation of the bracket shown in Figure 7.

Referring more in detail to the drawing, a framework of the chair is generally designated by the number 10. Front and rear rails of the framework are indicated by the numbers 12 and 13. A crossbeam parallel with these rails but disposed between same is shown at 14. The cross member at the top of the back of the chair is indicated at 15.

A resilient steel platform 16 is supported within the framework. The front side of the platform 16 is supported by springs 17 arranged at opposite sides of the framework of the chair. The springs 17 comprise coiled portions 18 having a lower projecting leg 19 that is fastened to the framework of the seat by means hereinafter de-

scribed. An upper, substantially parallel projecting leg 20 is looped through a clip 21 on the platform 16 and thereby held thereto. From the clip 21 the wires from the respective springs 17 are bent across at the front of the seat, as shown at 22 and 23. The wire ends 22 and 23 respectively have loops 24 and 25 arranged in same.

The ends 22 and 23 are longitudinally adjustable upon a plate 26 fastened to the front rail of the seat. Pins 27 and 28 hold the wire ends 22 and 23 against the plate 26 and separate the wires respectively. The ends 22, 23 are adjustable to accommodate different widths of seats to be placed on the platform 16, and different widths of platforms.

The means for supporting the lower projecting leg 19 comprises a bracket 30 that has a top member 31 that extends across the top of the rail 12 and has a front face 32 that is hooked over the rail 12. Pressed outwardly from the stock that forms the bracket 30 are socket members 33, 34 and 35. The end 36 of the leg 19 is bent downwardly substantially at right angles and inserted in the sockets 33, 34 and 35.

The rear of the platform 16 is supported by twin springs 37 and 38. These springs are tapered from end to end and are arranged in upright positions, although slightly at an incline, as shown in Figure 2. The lower ends of the springs are hooked around the rear portion of the platform 16, as shown at 39 and 40.

The upper ends of the springs 37 and 38 are tied to each other by a cord 41. Pulleys 42 and 43 disposed respectively above the springs 37 and 38 are arranged for the cord 41 to be passed around such pulleys. A saddle member 44 rides on the cord 41. A pull cord 45 connects with the saddle member 44 and is tied to a lever 46 after being passed around a pulley 47.

The lever 46 is pivoted at 48. An opposite arm 49 of the lever telescopes with a handle member 50. A pin 51 on the handle 50 slides in slots 52 on the arm 49. The front end of the handle 50 is held in position by a wire 53 that has a series of shoulders 54, 55 and 56 against which the handle 50 may engage. The wire 53 may be fastened on the inner side of the front rail 12 by any suitable means. Brads 57 are suggested in the drawing. A spring 58 resiliently holds the arm 49 up against the crossbeam 14.

The springs 37 and 38 each comprises a progressively stiffer resilient portion 60, 61 and 62. The spring portions are separated by plates 63 and 64 and an upper plate 65 is arranged at the top of each of said springs 37 and 38.

Cords 66 connect the top plate 65 with the next lower plate 63, in each of the springs. Cords 67 connect plate 63 with the plate 64, in each of the springs. In practice the cords 66 and 67 may be continuous but are held substantially at their mid-portions by clamps 70.

The plates 63, 64 have portions 72, 73 of their ends bent around adjacent turns of the spring 31, or 38, to maintain the plates in position. The bent portions 72 and 73 are arranged on opposite sides of the diameter of the spring (as best shown in Figure 4) in order to prevent lateral displacement of the plates.

Mid-portions 74 of the ends of the plates 63, 64 are bent in C shape, as shown in Figure 6. Washers 75 having sleeves 76 are arranged against the ends of plates 63, 64, with the sleeves 76 around the end portions 74. The cords 66, 67 pass around the sleeves 76.

In the operation of the construction, depression of the front side of the platform 16 is resiliently opposed by the springs 17 and the springs 24, 25. The ends 22, 23 of the spring wires are adjustable on the plate 26, to adjust the spring arrangement to platforms or seat-supports of various widths.

The handle 50 may be moved to any of its positions 54, 55 or 56, in order respectively to tighten the springs 37, 38, to have them at their mid-position of resilience, or to permit them to be at their loosest.

When a person sits on a seat (not shown) on the platform 16, the spring portions 60 first come into play (since they have less resistance to their extension than spring portions 61, which in turn have less resistance to their extension than the spring portions 62).

The spring portions 60 will probably not be extended to their maximum when a child is supported on a seat on the platform 16. However, when the spring portions have been extended to the maximum of the cords 66, the spring portions 61 come into play.

If the person is heavy, the spring portions 61 will be extended to the limit of the cords 67, and the spring portions 62 will take care of any excess weight thereover.

Adjusting the handle 50 places more, less, or a medium amount of tension in the springs, depending upon whether a greater, lesser, or a medium weight person is to occupy the seat.

While we have illustrated and described what we now regard as the preferred embodiment of our invention, the construction is, of course, subject to modifications without departing from the spirit and scope of our invention. We, therefore, do not wish to restrict ourselves to the particular form of construction illustrated and described, but desire to avail ourselves of all modifications which may fall within the scope of the appended claims.

Having thus described our invention, what we claim and desire to secure by Letters Patent is:

1. In a spring construction for supporting a seat-support within a framework, a coiled spring connected to the seat-support and the framework, and having portions of different strength to be successively brought into play as different pressures are applied to the seat-support, spaced plates, at least one of which is inserted between convolutions of the coiled spring to separate said portions thereof, hook means on the plates engaging the convolutions of the coiled spring to maintain the plates in position, and flexible cord means connected with the plates to limit exten-

sion of the coiled spring portions between adjacent plates.

2. In a spring construction for supporting a seat-support within a framework, a continuous helical spring of gradually increasing diameter and single gauge wire connected to support the seat-support within the framework, plates interposed between, and connected to, convolutions of the spring at spaced points in its length, to separate the spring into successive spring elements of different effective strengths, and flexible cord means connecting adjacent plates to limit extension of successive elements of the spring means.

3. In a spring construction for supporting a seat-support within a framework, coiled spring means of successively decreasing diameter, said coiled spring means being disposed to support the seat-support within the framework, plates clamped to convolutions of said spring means and arranged to separate the spring means into successive spring elements, said plates having portions projecting diametrically outwardly of the springs, and flexible cord means exteriorly of the springs connecting the projecting portions of adjacent plates to limit extension of successive elements of the spring means.

4. In a spring construction for supporting a seat-support within a framework, a single elongated, coiled tension spring of progressively gradually decreasing diameter but of wire of substantially the same gauge from end to end, to increase progressively the strength of the spring, said coiled spring supporting the seat-support within the framework, separators extending transversely through said spring at spaced points in its length and clamped to convolutions of the spring, for dividing the spring into effective lengths of different strength, and cord means tying together said separator portions of the coiled spring and permitting limited expansion successively of the said effective lengths of the spring.

5. In a spring construction for supporting a seat-support within a framework, spring means of progressively different strength connected at one end to the seat-support for supporting the latter within the framework and arranged to be progressively brought into play as different pressure is applied to the seat-support, and means connecting the other end of the spring means to the framework, including flexible adjusting connections and a lever mounted on the framework for adjusting said connections to progressively alter pressure on the spring, to alter the amount of pressure necessary to change the condition of the spring means by pressure on the seat-support.

6. In a spring construction for supporting a seat-support within a framework, coiled spring members of successively decreasing diameter connected at one end to the framework, means dividing said coiled spring means into successively effective lengths to support the seat-support within the framework and arranged to be successively brought into play as different pressures are applied to the seat-support, cord means connected to the other ends of the spring members to progressively extend the spring members and to progressively permit contraction thereof, and lever means on the framework and connected with the cord means to progressively extend and progressively permit contraction of the spring.

7. In a spring construction for supporting a seat-support within a framework, tension spring members connected at one end thereof to the

seat support to support the seat-support within the framework and including successive elements of different effective strength, flexible cord means connected to limit extension of successive elements of the spring means, cord means connected to one end of said members to extend progressive elements of the spring means and to progressively permit contraction of same, and lever means adjustably mounted on the framework and connected with the latter cord means to progressively extend and progressively permit contraction of the spring elements.

8. In a spring construction for supporting a seat-support within a framework, a pair of coiled tension springs of single gauge and successively

decreasing diameter, said coiled springs being connected at opposite ends thereof to the seat-support and the framework, means dividing the spring into successive portions of different strength for successive action as different pressures are applied to the seat-support, cord means having a common connection with one end of the springs to alter pressure upon the coiled springs, and a single lever adjustably mounted on the framework and connected with the cord means to progressively alter the pressure upon both coiled springs simultaneously.
